(57) **CLAIM**

The ornamental design for an electricity connector, as shown and described.

DESCRIPTION

FIG. 1 is a perspective view of an electricity connector showing my new design;

FIG. 2 is a front elevational view thereof;

FIG. 3 is a rear elevational view thereof,

FIG. 4 is a left side elevational view thereof,

FIG. 5 is a right side elevational view thereof,

FIG. 6 is a top plan view thereof;

FIG. 7 is a bottom plan view to that shown; and,

FIG. 8 is a perspective view of electricity connector, the broken lines shown are for illustrative purposes only and from no part of the claimed design.
